UNITED STATES PATENT OFFICE

1,933,976

INTEGRATING RELAY CIRCUIT

Malcolm P. Hanson, Washington, D. C., assignor,
by mesne assignments, to Wired Radio, Inc.,
New York, N. Y., a corporation of Delaware

Application December 22, 1928
Serial No. 327,995

3 Claims. (Cl. 250—27)

My invention relates to circuit arrangements in general and more specifically to circuit arrangements wherein electrical energy is integrated.

An object of my invention is to provide an integrating relay which will be responsive to a plurality of feeble electrical impulses.

Another object of my invention is to provide a circuit arrangement whereby a plurality of sources of signaling energy are caused to integrate and energize an associated load circuit.

A better understanding of the circuit arrangements of my invention can be had by referring to the specification following and to the accompanying drawing wherein:

15 Figure 1 is a diagrammatic view of the circuit arrangement of my invention and Fig. 2 shows a modification of the circuit arrangements of my invention.

My invention employs the glow discharge tube 20 of the type whereby a gas contained in an envelope is caused to conduct electrical energy under conditions producing ionization. The glow discharge device of the type employed in the circuit arrangements of my invention, comprises a container the gas in which is caused to ionize 25 at a critical potential of exciting energy. The container may be of glass, quartz or a silicate compound and the gas content may be rarefied helium, neon, krypton or other suitable gas. The 30 source of electrical energy may be direct or alternating current, either of which will cause the gas to ionize. When ionization of the gas occurs, a conducting path is provided between the electrodes suitably low in electrical resistance to 35 afford conduction of an appreciable value of electrical energy. The circuit arrangements of my invention make use of the fact that the energizing potential required to produce ionization of the gas is of a critical value. A better understanding 40 of the circuit arrangements of my invention can be had by referring to the accompanying drawing.

Fig. 1 is a diagrammatic illustration showing 45 schematically the circuit arrangements of my invention. A source of signaling energy is associated with the circuit 1. Circuit 1 is associated with circuit 2 which is the input circuit of thermionic tube 3. The output circuit of thermionic tube 3 includes glow discharge device 4, inductance 5, capacity 6 high resistance path 6a and source of electrical energy 7. Inductance 5 is associated with inductance 8 which is the input circuit of thermionic tube 9. The output circuit of thermionic tube 9 includes glow discharge 50 device 10, inductance 11, capacity 12 and source

of electrical energy 13. Load circuit 14 is associated with inductance 11 of the output circuit of thermionic tube 9. The operation of the circuit arrangements of my invention is as follows:

The source of signaling energy associated with the input circuit of thermionic tube 3 is amplified and charges the capacity 6 in the output circuit. The amplified signaling energy continues to charge capacity 6 until the potential so stored is sufficient to cause ionization of the gas contained in glow discharge tube 4. As soon as this potential is sufficient to produce ionization, glow discharge tube 4 offers a conductive path to the electrical energy thus stored in capacity 6 and the discharge surges through inductance 5. Inductance 5 is associated with the input circuit inductance 8 of thermionic tube 9. The surge of electrical energy caused by the integration of energy in capacity 6 and discharged through inductance 5 is amplified by thermionic tube 9 and the amplified energy in the output circuit of thermionic tube 9 is caused to charge a second capacity 12. When the surges have integrated to a sufficiently large value, the gas of glow discharge tube 10 is ionized and a conducting path 70 for the energy stored in capacity 12 is provided whereby the surge discharge is made possible through inductance 11. Inductance 11 is associated with any suitable load circuit 14. The critical potential necessary to produce ionization 75 of the gas in glow discharge device 4 is determined by the design. The energy stored in capacity 6 necessary to produce ionization will largely depend on the potential from source 7. It is therefore seen that the ionization of the gas 80 whereby the discharge of capacity 6 is provided depends upon the design of glow discharge device 4 and source of potential 7. It is further obvious that the frequency of the discharge through inductance 5 is a function of the value of the 85 source of energy in input circuit 2. Therefore the frequency of the discharge depends upon the design of the glow discharge tube and the critical potential necessary to produce ionization of the gas. This critical potential may be of any value 90 desired and may be counteracted by the selection of the proper value of source of energy 7. The control electrode of thermionic tube 9 will thus be energized by the surge of energy from inductance 5 and in the output circuit the energy 95 will be increased in value. The surges of energy from inductance 5, having a frequency determined as aforementioned, charge capacity 12. The charge is stored in capacity 12 where it integrates to a value as determined by the design 100 105 110

of glow discharge device 10 and the value of source of energy 13. The critical potential necessary to produce ionization of the gas in glow discharge device 10 may be of a higher order than the critical potential producing ionization of glow discharge device 4. When such is the case, the frequency can be reduced to a low value. The frequency of discharge through inductance 11 may be higher than the frequency of discharge 10 through inductance 5 or it may be of the same order. It is obvious that the energy can thus be integrated and increased in magnitude to a remarkable degree. The source of energy introduced into circuit 1 may be of the order of very feeble impulses. These impulses are caused to integrate and produce a source of electrical energy of sufficient amplitude to be utilized in many different ways.

Fig. 2 of the accompanying drawing shows a modification of the circuit arrangements of my invention. Similar reference characters have been used in Fig. 2 to identify corresponding parts as represented in Fig. 1. Capacity 6 is charged by the impulses in the output circuit. These impulses are caused to integrate until the critical ionization potential of glow discharge device 4 is reached. An electromagnet having a winding 5, which corresponds to inductance 5 of Fig. 1 is included in the output circuit. Winding 5 is energized by the surge of potential caused by the discharge of capacity 6 through the ionized gas path provided by glow discharge device 4. As heretofore mentioned the frequency of such energization may be determined by the values of capacity 6, source of potential 7 and the design of glow discharge device 4. The output circuit, responsive to the surges of electrical energy, includes a relay armature 15 which is actuated by the electromagnet. Armature 15 may be provided with suitable contacts for controlling the circuits 16, 17, and 18 or may take the form of suitable gear and pinion or other mechanical arrangements.

Many modifications of the circuit arrangements of my invention are possible without departing from the spirit of my invention. Any number of thermionic tubes and glow discharge tubes may be employed in combination to cause feeble electrical impulses to integrate to a determined value. It is to be understood that my invention shall not be limited to the accompany-

ing drawing or the foregoing specification but only as defined in the appended claims.

In the claims I have used the expression "input circuit" to designate the capacity 6 and resistance 6a, and the expression "output circuit" to indicate the inductance path 5 or relay winding 5. These terms are not to be confused with such terminology used to designate the grid and plate circuits of electron tubes.

What I claim as new and desire to secure by Letters Patent of the United States is as follows:

1. Means for converting electrical impulses that vary in intensity into electrical impulses that are of substantially constant intensity, but which vary in duration, comprising a variable impedance device, a source of potential and a condenser connected in series, a glow discharge tube and an output device connected in series across the terminals of said condenser and means for varying the impedance of said impedance device in accordance with the intensity of electrical impulses whereby the frequency of the intermittent current in said glow discharge tube circuit is proportional to the intensity of the controlling electrical impulses.

2. Means for converting electrical intensity variations into frequency variations, comprising a variable impedance device, means of varying the impedance of said device in accordance with the intensity of electrical impulses, a source of potential, a condenser, a glow discharge tube and an output device, said impedance device, source of potential and condenser being connected in series and said glow discharge tube and output device being connected in series across said condenser.

3. A signal receiving system comprising an electron discharge tube network having input and output circuits, a source of current, an inductive load and a glow tube in series in at least one of said output circuits, a condenser shunting both load and glow tube, and means for varying the impedance of said electron discharge tube in response to signals of varying intensity whereby said condenser is alternately charged and discharged and in consequence thereof the potential drop across the load and glow tube is varied above and below a critical point for activating said load.

MALCOLM P. HANSON.
